UNITED STATES PATENT OFFICE.

EDWIN D. WEARY, OF CHICAGO, ILLINOIS.

DESIGN FOR A MOSAIC FLOOR-COVERING.

SPECIFICATION forming part of Design No. 35,949, dated June 10, 1902.

Application filed April 26, 1902. Serial No. 104,817. Term of patent 3½ years.

To all whom it may concern:

Be it known that I, EDWIN D. WEARY, a citizen of the United States, residing at Chicago, in the county of Cook and State of Illinois, have invented and produced a new and original Design for Mosaic Floor-Covering, of which the following is a specification, reference being had to the accompanying drawing, forming a part thereof.

10 This invention is designed for floor-covering of the character which is termed "mosaic" by reason of the fact that it is produced by assembling on suitable backing elements whose lines of contiguity form the pattern.

15 The design is an interlocking pattern yielding to the eye the effect of zigzag lines in one direction intersecting similar zigzag lines in the transverse direction. The interlocking unit of form is the outline of the individual 20 elements whose contiguous edges yield this appearance when they are assembled on the backing. This unit of form is a double pentagon, and such units are assembled with the reentrant angles at the side of each occupied

25 by the end of the like unit. To complete the design within rectangular outlines, the full unit or double pentagon A in the vicinity of each corner has its reentrant angle occupied

30 by a half-unit or single pentagon B, two quarter-units or half-pentagons C being designed contiguous to the two sides of the end of the unit A, and a third quarter-unit or half-pentagon C' being designed occupying the interval and completing the rectangular corner between the half-unit B and the proximate 35 quarter-unit C. Similar arrangements of the elements are carried out along the margins running from each rectangle to the next—that is to say, each complete unit of form 40 proximate to the margin, having its end angle embraced by two quarter-units meeting end to end and each reentrant angle of each complete unit facing the marginal line, being occupied by a half-unit or single pentagon.

45 I claim—

The design for mosaic floor-covering herein shown and described.

In testimony whereof I have hereunto set my hand, in the presence of two witnesses, at Chicago, Illinois, this 9th day of April, A. D. 50 1902.

EDWIN D. WEARY.

In presence of—

CHAS. S. BURTON,
I. W. WESTERLAND.
